UNITED STATES PATENT OFFICE.

FRANK KUHN, OF DETROIT, MICHIGAN.

ELECTRICAL HEATING UNIT.

1,119,838.

Specification of Letters Patent. Patented Dec. 8, 1914.

Application filed March 8, 1913. Serial No. 752,874.

To all whom it may concern:

Be it known that I, FRANK KUHN, a citizen of the United States of America, residing at Detroit, in the county of Wayne and State of Michigan, have invented certain new and useful Improvements in Electrical Heating Units, of which the following is a specification, reference being had thereto in the accompanying drawings.

10 The invention relates to electric heaters and has particular reference to the construction of a heating unit which is adapted for use in connection with various constructions of electrically heated devices.

15 The invention consists in the construction as hereinafter set forth.

In the drawings: Figure 1 is a side elevation of the unit; Fig. 2 is a perspective view of a portion of the unit, showing the manner of engaging one of the resistor coils therewith; and Fig. 3 is a cross section of Fig. 2 showing a step in the formation of the unit.

20 A is a plate formed of a rigid electrically-insulating and heat-resisting material—such for instance as hard asbestos board.

25 B are resistor coils which are mounted upon the board A by providing the latter with series of perforations C so positioned as to receive the successive convolutions of the coil.

30 As has been stated, the material of which the board A is composed is substantially rigid, and it is also of a somewhat brittle nature so that the engagement of the coil with the perforations C is a difficult operation. To avoid this difficulty, I form at the end of each series of perforations C an obliquely-arranged slot D of sufficient size

40 to receive one convolution of the coil when arranged in alinement with the series of apertures. This permits the coil to be first

engaged with said slot, as shown in Fig. 3, and by then turning or twisting the coil about its axis, its end will be threaded successively through the apertures C until the entire coil is in engagement with the board. Where there are a number of the coils, such as B B', etc., arranged in parallel relation or otherwise upon the board, these may be connected in series or multiple by securing their opposite ends to intermediate binding posts E. These are preferably arranged upon the board intermediate adjacent series of perforations, and not only electrically connect the coils but mechanically hold them from displacement. To strengthen the structure, the edges of the board are preferably bound with metallic reinforcing strips F which may be of U-shaped section embracing the edges of the plates.

45 The unit as formed may be inserted in any suitable construction of electrically heated devices, and when connected in circuit heat will be developed in all of the coils and radiated from opposite sides of the plate.

50 What I claim as my invention is:

An electrical heating unit, comprising a flat board or plate of rigid electrically-insulating and heat-resisting material, having a series of perforations therein positioned to engage the successive convolutions of a resistor coil, and a slot adjacent the end of and in alinement with the series of perforations, of a size to receive the first convolution of the coil to permit of threading the same through said series of perforations.

55 In testimony whereof I affix my signature in presence of two witnesses.

FRANK KUHN.
